OSCILLATOR CIRCUIT

David M. Hodgin, Cedar Rapids, Iowa, assignor to Collins Radio Company, Cedar Rapids, Iowa, a corporation of Iowa

Application August 30, 1950, Serial No. 182,229

1 Claim. (Cl. 250—36)

This invention relates in general to oscillator circuits, and in particular to an oscillator which utilizes a stabilizer tube between the oscillating elements and the oscillator tube.

Sources of alternating signals are very important in the field of electronics today. It is also very important that the oscillations generated remain substantially constant at a predetermined frequency. The stability of the oscillator determines the stability of the output signal. Oftentimes a tank circuit comprising an inductance and capacitance is used to generate the desired oscillations and the output of the tank circuit is fed to an amplifier in order to obtain an appreciable signal that may be used. The inter-electrode capacitance of the amplifier changes with temperature and reflects back into the tank circuit so that a change of frequency occurs in response to change of the inter-electrode capacitance of the amplifier. The input capacity of the amplifier also varies with its gain, and since the tube may not always be operating in the linear portion of its characteristic curve, the gain and, consequently, the capacitance, will vary.

It is an object of this invention, therefore, to provide an oscillator in which changes of inter-electrode capacitance in the amplifier will not appreciably change the frequency of the tank circuit.

Another object of this invention is to provide an improved oscillator which has a stability of a high degree and wherein the variations in load cause a minimum amount of frequency shift.

Still another object of this invention is to provide means for stabilizing the effect of the oscillator tube on the oscillating elements.

A feature of this invention is found in the provision for a stabilizer tube which receives an output from a tank circuit and supplies an output to an oscillator tube. The oscillator receives an input from the plate of the stabilizer tube and a feed-back is furnished to the tank circuit from the oscillator tube.

Further objects, features, and advantages of this invention will become apparent from the following description and claim when read in view of the drawings, in which;

The figure is a wiring diagram illustrating the oscillator of this invention.

A tank circuit which has one side grounded and comprising the condenser C_1 and the inductance L_1 produces an output voltage E_1 whose frequency depends primarily on the values of C_1 and L_1 . A tube V_1 comprising a plate 10, cathode 11, and grid 12 receives voltage E_1 on its grid. A cathode resistor R_1 is connected between the cathode 11 and ground. A resistor R_2 is connected between the plate 10 of tube V_1 and B plus.

A second tube V_2 receives on its control grid 13 a signal from the plate 10 of V_1 through a blocking condenser C_2 . A grid leak resistor R_3 is connected between grid 13 and ground. The cathode 14 of tube V_2 is connected to ground and a resistor R_4 is connected between B plus and the plate 16. The screen grid 17 of tube V_2

2

is connected by a lead 18 through a blocking condenser C_3 to a tap 19 on the inductance L_1 . A resistor R_5 is connected between the screen grid 17 and B plus. It is to be noted that the grid 17 is not grounded, and thus is allowed to vary at a radio frequency rate.

The output of the oscillator is taken from the plate 16 of tube V_2 through the blocking condenser C_4 .

An example of usable values of the circuit components are:

10 Tube V_1 may be a 6C4
Tube V_2 may be a 6AU6

R_1 —3300 ohms

R_2 —1000 ohms

R_3 —150,000 ohms

15 R_4 —10,000 ohms

R_5 —56,000 ohms

B plus may be 200 volts

C_1 —570 micromicrofarads

C_2 —50 micromicrofarads

20 C_3 —0.01 microfarad

C_4 —100 micromicrofarads

L_1 is variable so that the oscillator may be tuned

The voltage E_1 developed across the tank circuit is fed to the control grid 12 of tube V_1 . The value of R_2 is less than R_1 and, therefore tube V_1 is operating at less than unity gain than in the linear portion of its characteristic curve. It is a linear class A amplifier with a gain of less than one. A 180 degree phase shift occurs in the applied signal between the control grid 12 and the plate 10.

The plate output of tube V_1 is supplied to the grid 13 of tube V_2 through the condenser C_2 . The values of C_2 and R_3 are chosen so that negligible phase shift occurs between plate 10 and grid 13.

35 Tube V_2 draws grid current on the positive voltage peaks. Since grid current is drawn the amplitude of the oscillation is self-limited.

The screen grid 17 is not grounded to radio frequency and is allowed to vary at any radio frequency rate.

40 A 180 degree phase shift occurs between the grid 13 and the screen grid 17. Thus, the voltage fed back through the lead 18 to the tank circuit is in phase with the voltage E_1 and thus adds directly with the voltage developed across the tank circuit and sustains oscillation as long as the over-all gain of the system is sufficient to overcome the combined losses of the system.

45 The stability of this oscillator is two to five times better than an oscillator which comprises merely a tank circuit and an oscillator tube. The increase in stability is due to the following factors:

50 1. The input capacity of tube V_1 varies very little with changes of filament and plate voltages. The reason for this is that the input capacity of a tube is equal to the capacitance from grid to cathode plus the capacitance from grid to plate plus the gain of the tube multiplied by the capacitance from grid to plate. In that the gain of the degenerative class A tube V_1 is less than one, variation of gain does not appreciably change the input capacity. Also, since tube V_1 operates in the linear portion of its characteristic curve, changes of filament and plate voltage do not appreciably effect the gain of the tube.

55 2. Since the grid 12 of the tube V_1 does not draw grid current at any time, there are no grid current pulses flowing through L_1 to ground. Such grid pulses introduce additional harmonic voltages in the tank circuit and such harmonic content has been shown by Llewellyn to increase instability. (See Constant Frequency Oscillator—Proceedings of I. R. E. vol. 19, No. 12, Dec. 30, 1930.)

60 3. The input capacity changes of tube V_2 are effectively blocked out by tube V_1 , since it is effectively in series with the grid to ground input capacity of tube V_1 . This reduces the effective capacity change.

Thus, it is seen that the addition of the stabilizer tube V_1 , which operates with a low gain, appreciably cuts down the capacitance changes of tube V_2 that would normally cause a change in the frequency of oscillation of the tank circuit. The stabilizing action of tube V_1 will minimize frequency shift as the load from the oscillator is varied.

Although this invention has been described with respect to a preferred embodiment thereof, it is not to be so limited as changes or modifications may be made therein which are within the full intended scope of the invention as defined by the appended claim.

I claim:

An oscillator circuit comprising, a tank circuit having one end grounded, a first phase-inverting amplifier having an electron tube with at least a control grid, wherein the control grid is connected to the ungrounded side of the tank circuit, said phase-inverting amplifier having a voltage gain of less than one to minimize its input plate-to-grid interelectrode capacitance, a second phase-inverting amplifier having an electron tube with at least

a control grid and a screen grid, wherein the control grid of the second electron tube is connected to receive the plate output of the first electron tube, and feedback means coupled between the screen grid of the second electron tube and the tank circuit to provide oscillatory positive feedback, whereby a load connected to the plate of the second amplifier is isolated from the tank circuit through the large plate-to-grid impedance of the first amplifier.
